UNITED STATES PATENT OFFICE.

GEORGE H. GILMAN, OF CLAREMONT, NEW HAMPSHIRE, ASSIGNOR TO SULLIVAN MACHINERY COMPANY, OF CLAREMONT, NEW HAMPSHIRE, A CORPORATION OF MASSACHUSETTS.

ROCK-DRILL.

1,382,779.

Specification of Letters Patent. Patented June 28, 1921.

Application filed August 27, 1915, Serial No. 47,570. Renewed June 16, 1919. Serial No. 304,726.

To all whom it may concern:

Be it known that I, GEORGE H. GILMAN, a citizen of the United States, and a resident of Claremont, county of Sullivan and State 5 of New Hampshire, have invented an Improvement in Rock-Drills, of which the following description, in connection with the accompanying drawings, is a specification, like characters on the drawings representing like parts.

This invention relates to cutting tools, and more especially, though not exclusively, to rock drilling machines of that class in which liquid and gaseous fluid may be supplied to the drilled hole to lay the dust, cleanse the drilled hole, and expel the cuttings therefrom.

My invention will be best understood by reference to the following description, when 20 taken in connection with the accompanying drawings of one illustrative embodiment thereof, while its scope will be more particularly pointed out in the appended claims.

25 In the drawings:

Figure 1 is a plan, partly in section, of a rock drilling machine embodying my invention;

Fig. 2 is a longitudinal section, partly in elevation, on line 2—2 of Fig. 1;

Fig. 3 is a sectional view, partly in elevation, on an enlarged scale, on line 3—3 of Fig. 2;

Fig. 4 is a detail, central, longitudinal section, on an enlarged scale, on line A—A, Fig. 3, of the rear end of the machine showing the throttle valve in its closed position;

Figs. 5 to 8 inclusive, are longitudinal sections showing the valve in its various positions of adjustment. Each of these figures comprises two views, viz: A and B on lines A—A and B—B respectively of Fig. 3.

Referring to the drawings, and to the embodiment of my invention which I have 45 selected for illustration, I have there shown a rock drilling machine comprising suitable drill-bit percussion means, herein in the form of a pressure fluid engine having a cylinder 9, in which a piston 10 is mounted to reciprocate. The piston may actuate a drill-bit 11 percussively in any appropriate manner, but for the purposes of illustration, I have shown a machine of the indirect or hammer type, in which the piston delivers

a rapid succession of blows on the inner 55 end of the drill-bit, which is loosely held in its path. In the illustrative example, the piston is provided with a hammer bar or extension 12, having splined connection with a suitable chuck 13, and 60 provided with suitable rotating mechanism 14, similar to that shown in United States Letters Patent No. 1,034,010, dated July 30, 1912. Since the rotating mechanism forms no essential part of my present 65 invention, it will be unnecessary here to describe the same, it being understood that the connection between the piston and rotating chuck is such that the reciprocatory movement of the piston is accompanied by a 70 step-by-step rotative movement thereof, which in turn causes a step-by-step rotative movement of the chuck and the drill-bit held thereby, the drill-bit for this purpose being provided with suitable means, such 75 for example as a pair of lugs 14', engaging slots 15 provided in the chuck. The latter, as is customary, may be, and is herein, provided with a chuck bushing 16, which holds the drill-bit and defines its initial movement. 80 In the example shown, the cylinder is provided with an elongated front cylinder head 17, which incloses and forms a mounting for the chuck and its associated parts.

The movements of the piston may be controlled by any suitable means, as by the piston itself, or by a suitable pressure fluid actuated valve 18 of any appropriate form, such, for example, as that forming the subject-matter of United States Letters 90 Patent No. 1,095,848, dated May 5, 1914. This valve is annular, or shell-like in form, and located preferably at the rear of and in line with the piston, a rear projecting portion 19 of which is adapted to enter the 95 valve and partly close the same on the rear stroke of the piston.

The valve controls the admission of pressure fluid to opposite ends of the cylinder from a pressure fluid supply space 20, as 100 well as the exhaust from the opposite ends of the cylinder through an exhaust outlet 21. Suitable gaseous fluid, preferably compressed air, is supplied to the pressure supply space 20 by a flexible pipe 22, and is 105 under the control of a throttle valve, which I will presently describe.

The drill-bit 11 is provided as usual with

cutting edges 23, and to the end that the cuttings may be expelled, the dust laid, and the cutting edges kept cool during the operation of the drill, the drill-bit is made 5 hollow, and, as herein shown, is provided with an axial passage 24 extending from end to end. To supply the hollow drill-bit with liquid or gaseous fluid, or both, under pressure, I may employ two tubes 25 and 26, one 10 adapted to supply liquid and the other gaseous fluid. These tubes may be, and preferably are, coaxially arranged, and extend through a longitudinal and preferably axial perforation 27, provided in the 15 piston. The inner tube 25, which in the present case is intended to supply liquid to the interior of the drill-bit, extends into and terminates within the latter, and is of such diameter as to leave an annular space 20 28 of small area between the tube and the surrounding internal surface of the axial hole 24 of the drill-bit to provide for the entrance of gaseous fluid at the rear end of the drill-bit, whereby the liquid and 25 gaseous fluid may be separately conducted into and united within the drill-bit. The outer tube 26, which is intended to conduct the gaseous fluid, may and preferably does terminate at the rear of the drill-bit, and 30 at a sufficient distance therefrom so that the gaseous fluid may build up within a chamber 29 within the drill chuck a body of gaseous fluid under pressure which will supply the bore of the drill-bit, and in addition, what is equally important and one of 35 the particular features of my invention, will serve to prevent the entrance of water and sludge into the cylinder. This is very apt to take place when drilling upwardly 40 directed holes, and, where the water and sludge find their way between the drill-bit and the chuck bushing into the space at the rear of the drill-bit, much damage may result to the tool if the water and sludge find 45 their way along the hammer bar and into the cylinder proper.

The tubes 25 and 26 extend rearwardly into, and are supported in some appropriate manner within a rear cylinder head or head 50 block 30. The inner tube extends some distance rearwardly beyond the outer tube, and communicates through passages 101 (Fig. 4) and 102 with a valve 65 to which liquid is conducted through the passage 81 from 55 any suitable water supply typified by the coupling 68 connected to a water supply hose 64.

Gaseous fluid, preferably air, is conducted to the outer tube 26 through the passage 103 60 from the chamber 104, which communicates with the valve mechanism hereinafter described, through the radial passages 105, the passage 106 in the plug 107, the chamber 108, and the passage 109.

65 I have found it advantageous to locate

several of the before described passages in a valve containing block 110 in which I preferably screw a cylindrical air and water distributing block 111, adapted to receive the rear ends of the air and water tubes 70 25 and 26. I may secure these tubes and prevent leakage by providing in the block 111 a cylindrical opening 112, which may contain the packing ring 113, the gland 114 carried by the head of the water tube 25, 75 the annular ring 115, the gland 116 carried by the air tube 26, the packing ring 117 and the gland 118 which is pressed against the packing disk 119 when the block 111 is screwed in place, thereby pressing together 80 and holding in proper relation all the members contained in the cylindrical opening 112. I preferably proportion the annular ring 115 and the gland 116 so that an air chamber 120 is provided back of the air tube 85 25. In the annular ring 115 there may be turned the annular groove 121 which may be connected with the air chamber 120 by radial ports 122. Around the block 111 I prefer to provide a packing ring 123. In 90 the rear of the block 111 is another cylindrical opening into which the plug 107 is screwed. This plug may be provided with a hexagonal head 124 which may serve, as illustrated, to retain a head 125 serving to 95 close the rear opening of the head block 110.

When it is desired to disassemble the machine the hexagonal head 124 is turned, thereby unscrewing the plug 107 and releasing the head 125. The block 111 may then 100 be unscrewed and withdrawn from the head block 110, thereby permitting the withdrawal of the tubes 25 and 26 and the associated parts.

In order that the supply of motive fluid 105 to the cylinder, the supply of liquid to the drilled hole, and the supply of gaseous fluid to the drilled hole may be coördinately controlled, I preferably place them under the control of a single valve 65, which, as will 110 be hereinafter described, in its closed position (Fig. 5) shuts off entirely the supplies of both gaseous fluid and water from the tool. When the valve 65 is turned to the second position (Fig. 6) air is admitted to 115 the air tube 25 and water to the water tube 26. In the third position (Fig. 7) air and water are still admitted to the tubes while the port to the hammer drill operating mechanism is partially opened. The fourth position (Fig. 8) completes the opening of the port to the drill operating mechanism while 120 leaving open the air and water supply ports to the tubes. In Figs. 5, 6, 7 and 8, 126 represents the air supply chamber, 127 the air 125 controlling portion, and 128 the water controlling portion of the valve 65. The air supply to the tube passes out through the port 129. Water is introduced to the valve 65 through the port 130, and passes out 130

through the port 131 along the passage 132 to the passage 133. The water and air ports to the tubes are open, as shown in Figs. 6, 7 and 8. The air port to the drill is partly 5 open in Fig. 7 and fully open in Fig. 8. In Fig. 1 all ports are closed.

I have found this form of control to be particularly advantageous when used in connection with the other mechanism herein described as contained in the head block. The construction and organization is well adapted to withstand the jar and shock inseparable from rock drill operation. The relative arrangement of air and water supply to the 15 tubes whereby the air supply to the air tube 25 passes around the more exposed passages, while the water is confined to better protected passages, insures against the objectionable exterior leakage of water. Interior 20 leakage is prevented by the air under pressure which prevents such leakage even if the packing provided proves defective. The construction is simple, not likely to get out of order, cheap to manufacture, easy to assemble and disassemble and very effective in 25 operation.

While I have herein shown and described one specific embodiment of my invention for illustrative purposes, and have disclosed and 30 discussed in detail the construction and arrangement incidental to one specific application thereof, it is to be understood that the invention is limited neither to the mere details or relative arrangement of parts, nor 35 to its specific embodiment herein shown, but that extensive deviations from the illustrated form or embodiment of the invention may be made, within the scope of the claims, without departing from the principles of the 40 invention.

Having thus described my invention, what I claim and desire by Letters Patent to procure is:—

1. A rock drill comprising, in combination, 45 a hollow drill bit; drill bit percussion means; tubular means for conducting air and water to said drill bit; a manually operable controlling means for controlling admission of air and water to said tubular means; an air passage connecting said controlling means with said tubular means; and a water passage connecting said controlling means with said tubular means, said air passage being located in the rear of said water passage and so disposed as to prevent leakage 50 therefrom.

2. A rock drill comprising, in combination, 55 a hollow drill bit; drill bit percussion means; an air conducting tube disposed longitudinally of said drill for conducting air to said drill bit; a water conducting tube passing through said air conducting tube and extending rearwardly therefrom; a head receiving the rear ends of both of said tubes; 60 a water passage in said head for conducting

water to said water tube; and means including an air passage in said head positioned rearwardly from said water passage for preventing leakage therefrom.

3. In a rock drill having a hollow drill bit 70 and percussive means, the combination of two tubes, one within the other, for conducting water and gaseous fluid to said hollow drill bit, and terminating rearwardly in a head having a removable exterior portion, 75 water conducting means for conducting water to one of said tubes, and means including an air chamber in the rear of said head adjacent said removable portion for preventing leakage from said water conduct- 80 ing means.

4. In a rock drill having a hollow drill bit and percussive means, the combination of a rear head, tubular means for conducting air and water from said head to said hollow drill 85 bit, said tubular means terminating in said head, a removable portion secured to said head, and means including an elastic pressure fluid containing chamber adjacent said removable portion for preventing leakage of 90 the water.

5. In a rock drill having a hollow drill bit and percussive means, the combination of tubular fluid conducting means for conducting fluid to said drill bit, and a rear cylinder 95 head having a chamber aligned with said conducting means, supporting means for said conducting means positioned in said chamber and having provision for supplying liquid to said conducting means, an opening in 100 the rear of said chamber through which said supporting means and said tubular means may be withdrawn, a cover for said opening, and an elastic pressure fluid containing chamber intermediate said supporting means and said cover.

6. In a rock drill, the combination of a cylinder, percussive means, a hollow drill steel, a rear head, tubular means for conducting gaseous fluid and a liquid from said rear head to said drill steel, a tubular means receiving member substantially aligned with said tubular means and removably secured in said rear head, and clamping means for simultaneously clamping said tubular means 110 to said rear head upon movement of said receiving member.

7. In a rock drill, the combination with a cylinder, percussive means therein, a hollow drill steel, concentrically disposed gaseous 115 fluid and liquid tubes communicating therewith, a rear head, a plug adjustable therein and inclosing the rear ends of said tubes, and means disposed within said plug and carried upon the ends of said tubes for clamping both of the latter to said head upon adjustment of said plug.

8. In a rock drill, the combination with a cylinder, percussive means therein, a hollow drill steel, concentrically disposed gaseous 120 fluid and liquid tubes communicating therewith, a rear head, a plug adjustable therein and inclosing the rear ends of said tubes, and means disposed within said plug and carried upon the ends of said tubes for clamping both of the latter to said head upon adjustment of said plug.

130

- fluid and liquid tubes communicating therewith, a rear head, a plug adjustable therein and inclosing the rear ends of said tubes, and means carried in said plug for spacing apart 5 the ends of said tubes and clamping the same to said head upon adjustment of said plug.
9. In a rock drill, the combination with a cylinder, percussive means therein, a hollow drill steel, concentrically disposed gaseous 10 fluid and liquid tubes communicating therewith, a rear head, a plug inclosing the rear ends of said tubes, means within said plug and disposed around the ends of said tubes for clamping the latter to said head upon adjustment of said plug, and means for supplying gaseous fluid and liquid to said tubes including separate passages through said plug.
10. In a rock drill, the combination with 20 a cylinder, percussive means therein, a hollow drill steel, concentrically disposed gaseous fluid and liquid tubes communicating therewith, a rear head; a plug inclosing the rear ends of said tubes, means within said plug and disposed around the ends of said tubes for clamping the latter to said head upon adjustment of said plug, means for supplying gaseous fluid and liquid to said tubes including separate passages through 30 said plug, and sealing means surrounding said plug at one side of said liquid passages.
11. In a rock drill, the combination of a cylinder, percussive means, a hollow drill steel, a rear head, tubular means for conducting gaseous fluid and a liquid from said rear head to said drill steel, a tubular means receiving member substantially aligned with said tubular means and removably secured in said rear head, gaseous fluid and liquid 35 40 conducting means in said receiving member for conducting gaseous fluid and liquid to said tubular means, and a valve for controlling the flow of gaseous fluid and liquid.
12. In a rock drill, a cylinder, percussive 45 means therein, a hollow drill steel, concentrically disposed gaseous fluid and liquid tubes communicating therewith, a rear head, an adjustable plug in said head inclosing the rear ends of said tubes, clamping means controlled by said plug for clamping both of said tubes to said head upon adjustment of said plug, a removable member inclosing the end of said plug, and means for clamping the latter to said plug.
- 55 13. In a rock drill, a cylinder, percussive means therein, a hollow drill steel, concentrically disposed gaseous fluid and liquid tubes communicating therewith, a rear head, a removable plug inclosing the rear ends of 60 said tubes, means inclosed by said plug for clamping said tubes to said head upon movement of said plug, and a removable member inclosing the end of said plug, said head and plug and removable member being provided with passages for supplying gaseous
- fluid to one of said tubes and said head and plug being provided with inner passages for supplying liquid to the other tube.
14. In a rock drill, the combination of a cylinder, percussive means, a hollow drill 70 steel, a rear head, a water tube for conducting water from said rear head to said drill steel, an air tube for conducting air to said drill steel, one of said tubes being located within the other and extending rearwardly 75 therefrom, a removable member located in said rear head and supporting an air tube support and a water tube support, packing operatively positioned between said air tube support and said water tube support, and means for compressing said packing.
15. In a rock drill, the combination of a cylinder, percussive means, a hollow drill steel, a rear head, a water tube for conducting water from said rear head to said drill 80 85 steel, an air tube for conducting air to said drill steel, one of said tubes being located within the other and extending rearwardly therefrom, a removable member located in said rear head and supporting an air tube support and a water tube support, packing operatively positioned between said air tube support and said water tube support, and compression means whereby movement of said removable member in the direction of 90 its axis compresses said packing.
16. In a rock drill, the combination of a cylinder, percussive means, a hollow drill steel, a rear head, a water tube for conducting water from said rear head to said drill 100 105 steel, an air tube for conducting air to said drill steel, one of said tubes being located within the other and extending rearwardly therefrom, a removable member located in said rear head and supporting an air tube support and a water tube support, packing operatively positioned between said air tube support and said water tube support, and compression means whereby rotative movement of said removable member tightens said 110 packing.
17. In a rock drill, the combination of a cylinder, percussive means, a hollow drill steel, a rear head, a water tube for conducting water from said rear head to said drill 115 steel, an air tube for conducting air to said drill steel, one of said tubes being located within the other and extending rearwardly therefrom, a removable member located in said rear head and operatively supporting 120 said air tube and said water tube, an opening in the rear of said rear head whereby said removable member may be removed, a cover for said opening, and an air chamber adjacent the joint between said rear head 125 and said cover.
18. In a rock drill, the combination of a cylinder, percussive means, a hollow drill steel, a rear head, a water tube for conducting water from said rear head to said drill steel, 130

- an air tube for conducting air to said drill steel, one of said tubes being located within the other and extending rearwardly therefrom, a cylindrical member removable 5 through an opening in said rear head and in which said tubes terminate at their rear ends, said member having separate passages therein for supplying air and water to said tubes and a cover for said opening.
- 10 19. In a rock drill, the combination of a cylinder, percussive means, a hollow drill steel, a rear head, a water tube for conducting water from said rear head to said drill steel, an air tube for conducting air to said 15 drill steel, one of said tubes being located within the other and extending rearwardly therefrom, a removable member located in said rear head and operatively supporting said air and water tubes and having separate 20 passages communicating therewith, and a single control valve providing ports for simultaneously conducting air to one of said tubes and water to the other of said tubes.
- 20 20. In a rock drill, the combination of a cylinder, percussive means, a hollow drill 25 steel, a rear head, a water tube for conducting water from said rear head to said drill steel, an air tube for conducting air to said drill steel, said water tube being located 30 within the other and extending rearwardly therefrom, a removable member located in said rear head and operatively supporting said air and water tubes and having separate 35 passages communicating therewith, and a single control valve providing ports for simultaneously conducting air to one of said tubes and water to the other of said tubes without admitting air to said percussive means.
- 40 21. In a rock drill, the combination of a cylinder, percussive means, a hollow drill steel, a rear head, a water tube for conducting water from said rear head to said drill steel, an air tube for conducting air to said 45 drill steel, said water tube being located within the other and extending rearwardly therefrom, a removable member located in said rear head and operatively supporting said air and water tubes and having separate 50 passages communicating therewith, and a single control valve providing ports for simultaneously conducting air to one of said tubes, water to the other of said tubes and air to said percussive means.
- 55 22. In a rock drill, the combination of a cylinder, percussive means, a hollow drill steel, a rear head, a water tube for conducting water from said rear head to said drill steel, an air tube for conducting air to said 60 drill steel, said water tube being located within said air tube and extending rearwardly therefrom, a removable member located in said rear head and operatively supporting said air and water tubes and having 65 separate passages communicating therewith, and a single control valve providing ports for simultaneously conducting air to one of said tubes, water to the other of said tubes and air to said percussive means.
- 70 and a single control valve providing ports for simultaneously conducting a full supply of air to said air tube, a full supply of water to said water tube, and a restricted supply of air to said percussive means.
- 75 23. In a rock drill, the combination with a cylinder, of percussive means therein, a hollow drill steel, a rear head for said cylinder, separate coaxially disposed gaseous fluid and liquid conducting tubes in said cylinder communicating with said steel, and means for securing said tubes in rigid relation to said head comprising a removable member disposed in said head between the ends of said conducting tubes and operative 80 positively to prevent movement of said ends toward each other.
- 85 24. In a rock drill, the combination with a cylinder, of percussive means therein, a hollow drill steel, a rear head for said cylinder, separate coaxially disposed gaseous fluid and liquid conducting tubes communicating with said steel and terminating at their rear ends in said head, a removable spacing member disposed in said head between the ends of said conducting tubes and operative 90 positively to prevent movement of said ends toward each other, and detachable means for clamping said elements in said head.
- 95 25. In a rock drill, the combination with a cylinder, of percussive means therein, a hollow drill steel, a rear head for said cylinder, separate coaxially disposed gaseous fluid and liquid conducting tubes in said cylinder communicating with said steel, means for securing said tubes in rigid relation to said head comprising a removable spacing member disposed in said head between the ends of said conducting tubes and positively preventing their movement toward each other, and fluid conducting means in 100 said spacing member.
- 105 26. In a rock drill, the combination with a cylinder, of percussive means therein, a hollow drill steel, a rear head for said cylinder, separate coaxially disposed gaseous fluid and liquid conducting means in said cylinder extending from said head and communicating with said steel, a spacing member disposed in said head between the ends of said conducting means and positively preventing their movement toward each other, and a single clamping member for retaining 110 said conducting means in said head.
- 115 27. In a rock drill, the combination with a cylinder, of percussive means therein, a hollow drill steel, a rear head for said cylinder, separate coaxially disposed gaseous fluid and liquid conducting means communicating with said steel and terminating in said head, a spacing member disposed in said head between the ends of said conducting means and positively preventing their movement toward each other, a single clamp- 120
- 125
- 130

ing member for retaining said conducting means in said head, and fluid conducting means in said spacing member.

28. In a rock drill, the combination with 5 a cylinder, of percussive means therein, a hollow drill steel, a rear head, separate coaxially disposed gaseous fluid and liquid conducting means communicating with said steel and terminating in said head, spacing 10 means in said head between the ends of said conducting means, a single clamping member for retaining said conducting means in said head, and fluid conducting means in said spacing means and clamping member. 15 29. The combination with a percussive tool, of a hollow drill steel, and means for supplying a cleansing fluid thereto comprising a rear head, a gland therein having a socket formed therein, a plurality of tubes 20 detachably secured in said socket, said gland and tubes being insertible into said head from the rear thereof, and means for conducting fluid to said tubes.

30. The combination with a percussive tool, of a hollow drill steel, and means for 25 supplying a cleansing fluid thereto comprising a rear head, a gland therein having a socket, a plurality of fluid conducting means communicating with said socket, and a plurality of tubes 30 detachably secured in said socket in communication with said fluid conducting means.

31. The combination with a percussive tool, of a hollow drill steel, and means for 35 supplying a cleansing fluid thereto comprising a rear head, a gland therein having a socket, a plurality of tubes extending into said head, spacing means therefor disposed in said socket, and a packing surrounding 40 one of said tubes and compressed upon movement of said gland.

32. In a rock drill, the combination with a rear cylinder head, of a plurality of coaxially disposed tubular gaseous fluid and 45 liquid conducting means extending into the same, an axially recessed clamping member having a passage communicating with one of said tubes, and a spacing member spacing the ends of the tubes extending into the recess in said clamping member and having a passage communicating with another of said tubes.

33. In a rock drill, the combination with a cylinder, of percussive means therein, a hollow drill steel, a rear head, a plurality of coaxially disposed gaseous fluid and liquid conducting means disposed axially of said piston, spacing means between the same, a clamping member in said head and axially 55 aligned with said spacing means and removable through said head, and a cover plate inclosing the outer end of said clamping member.

34. In a rock drill, the combination with 60 a cylinder, percussive means therein and a

hollow drill steel, of separate coaxially disposed gaseous fluid and liquid conducting tubes to conduct cleansing fluid for said steel, and a member having lateral and end contact with one of said tubes and end contact only with the other thereof and cooperating to maintain them in spaced relation. 70

35. In a rock drill, the combination with a cylinder, percussive means therein and a hollow drill steel, of separate coaxially disposed gaseous fluid and liquid conducting tubes to conduct cleansing fluid for said steel, each of said tubes being provided with an annular collar, and spacing means between said collars. 75

36. In a rock drill, the combination with a cylinder, percussive means therein and a hollow drill steel, of separate coaxially disposed gaseous fluid and liquid conducting tubes to conduct cleansing fluid for said steel, each of said tubes being provided with an annular collar and spacing means between said collars, said spacing means cooperating to supply fluid to one of said tubes. 80 90

37. In a rock drill, the combination with a cylinder, percussive means therein and a hollow drill steel, of separate coaxially disposed gaseous fluid and liquid conducting tubes to conduct cleansing fluid for said steel, and spacing means disposed between the rear ends of said tubes, said tubes having portions abutting against the opposite ends of said spacing means. 95

38. In a rock drill, the combination with a cylinder, percussive means therein and a hollow drill steel, of separate coaxially disposed gaseous fluid and liquid conducting tubes to conduct cleansing fluid to said steel, and spacing means into one end of 100 which one of said tubes partially projects and with which a portion of said tube also has lateral engagement and against the opposite end of which a portion of said other tube abuts. 105 110

39. In a rock drill, the combination with a cylinder, of percussive means therein, a hollow drill steel, a rear head, separate coaxially disposed gaseous fluid and liquid conducting tubes to conduct cleansing fluid 115 to said steel, spacing means in said head between the ends of said conducting tubes, and detachable means for clamping one of said elements against said spacing means.

40. In a rock drill, the combination with a cylinder, percussive means therein and a hollow drill steel, of separate coaxially disposed gaseous fluid and liquid conducting tubes for supplying cleansing fluid to said steel, and means for holding said tubes in 120 said cylinder comprising spacing means disposed between the rear ends of said tubes, said tubes having portions abutting against 125 spacially separated opposed surfaces of said spacing means. 130

41. In a rock drill, the combination with a cylinder, a piston reciprocable therein, a hollow drill steel, coaxially disposed gaseous fluid and liquid conducting tubes for supplying cleansing fluid to said hollow drill steel, the inner of said tubes projecting rearwardly further than the outer thereof, a rear head, a plug adjustable coaxially with respect to said tubes, a flange upon the inner one of said tubes, a perforated collar through which said inner tube extends, and a packing surrounding the outer of said tubes, said plug being adjustable to clamp said flange into engagement with said collar and to compress said packing about said outer tube.

42. In a rock drill, the combination with a cylinder, a piston reciprocable therein, a hollow drill steel, coaxially disposed gaseous fluid and liquid conducting tubes for supplying cleansing fluid to said hollow drill steel, the inner of said tubes projecting rearwardly farther than the outer one thereof, a rear head, a plug adjustable therein longitudinally with respect to said tubes, flanges adjacent the rear ends of each of said tubes, and a perforated collar through which the inner of said tubes extends and disposed between said flanges, said plug being adjust-

able to clamp said perforated collar in tight engagement with the flanges on said tubes. 30

43. In a rock drill, the combination with a cylinder, a piston reciprocable therein, a hollow drill steel, coaxially disposed gaseous fluid and liquid tubes for supplying cleansing fluid to said hollow drill steel, the inner of said tubes projecting rearwardly farther than the outer thereof, a rear head, a plug adjustable therein longitudinally with respect to said tubes, a perforated collar having a recess therein, the inner of said tubes extending longitudinally through said collar and the outer of said tubes projecting into said recess, a flange upon the inner of said tubes engaging the rear end of said collar, and a packing surrounding the outer of said tubes forwardly of said collar, said plug being adjustable to clamp said flange into engagement with said collar and to compress said packing about the outer tube. 40

In testimony whereof, I have signed my name to this specification, in the presence of two subscribing witnesses.

GEORGE H. GILMAN.
